UNITED STATES PATENT OFFICE.

EZEKIEL C. S. COBB AND SAMUEL T. MACMULLEN, OF WILMINGTON, DELAWARE.

PNEUMATIC SHUTTLE-THROWER.

SPECIFICATION forming part of Letters Patent No. 781,632, dated February 7, 1905.

Application filed November 28, 1903. Serial No. 182,966.

To all whom it may concern:

Be it known that we, EZEKIEL C. S. COBB and SAMUEL T. MACMULLEN, citizens of the United States, residing at Wilmington, in the county of Newcastle and State of Delaware, have invented new and useful Improvements in Pneumatic Shuttle-Throwers, of which the following is a specification.

This invention relates to pneumatic shuttle throwers or pickers for looms.

The object of the invention is to construct a shuttle thrower or picker in which the shuttle shall be thrown from both sides of the loom with absolute uniformity by pneumatic pressure; also, to furnish a pneumatic check or buffer to the shuttle-thrower which may be adjusted to give any required elasticity and resistance; also, to improve pneumatic shuttle-throwers in various particulars, as will be stated in the claims.

Figure 1 is the front elevation of so much of a loom as is necessary to give a general idea of the arrangement of the shuttle-thrower thereon. Fig. 2 is a sectional view of a special valve employed to control the entrance and exit of air to and from the cylinders of the thrower. Fig. 3 is an elevation of the parts composing the shuttle-thrower. Fig. 4 is a longitudinal section of one of the cylinders and its piston and rod. Fig. 5 is a section of the buffer or check, and Fig. 6 is a cross-section of the same. Fig. 7 is a broken part of a longitudinal section indicating the lay and its support.

The drawings do not show sizes or proportions of parts, but are intended to guide a mechanic skilled in this art in the construction of the device.

The piston-rod 1 extends across the loom. As shown in Fig. 1, it is above the position of the warp; but such position might readily be changed or reversed. Piston-rod 1 has a piston 2 at each end. Each piston 2 fits a pneumatic cylinder 3, which cylinder is suitably supported on the hand-rail of the loom. The pistons 2 are suitably packed to work air-tight or with very little leakage in the cylinders 3. At the outer end of each cylinder 3 and connected by a suitable pipe or duct there

is a valve 4. The valve 4 is in communication with a supply of compressed air by means of a hose 5 or other suitable connection. The valve 4 has a stem 6 extending through the casing and provided with a plug 8, which closes or opens the passage in diaphragm 9, through which air is admitted to cylinder 3. The stem 6 passes through a stuffing-box 10 to a valve-lever 11, which lever is pivoted outside the casing both to the valve-stem and casing or to a support 12 on the casing, enough lost motion being allowed at the pivots to permit the vertical play of the valve-stem. The valve-stem is pressed upward to close plug 8 by spring 13, seated within the casing and bearing on said plug. The lower end of the valve-stem is hollow and extends down through a stuffing-box 14.

A cross passage or vent 16 in the valve-stem is just within the casing and open when the plug 8 is closed into its seat in diaphragm 9; but this vent 16 is closed whenever stem 6 is pressed down, so that the vent 16 comes within the wall of the casing or the cap 17, forming an extension of the valve-casing. If there be air-pressure in the upper chamber of the valve, then depressing stem 6 the vent 16 will be closed and plug 8 opened, and the air will pass through the valve into cylinder 3, driving the piston 2 along in said cylinder. This depression of stem 6 is in practice effected by a moving part of the machine, (as an arm worked by the batten or by the harness,) and the air admitted to cylinder 3 drives the piston 2 and rod 1 toward the other side of the loom.

The piston-rod 1 has rigid arms 22 22, which connect the piston-rod 1 to the throwing-bar 21. This bar 21 has pickers or strikers 23 at each end, and these pickers or strikers alternately engage the shuttle and throw it across the loom in usual manner.

It will be understood that the valves, cylinders, and pistons at each end of the piston-rod 1 are duplicates, but that the contact-pieces 20, however they may be operated, only open the valves 4 alternately.

Midway of the piston-rod the buffer or check-cylinder 30 is suitably supported on the

hand-rail of the lay of the loom. On the piston-rod 1 are two buffer-pistons 31, each adapted to enter an open-ended chamber in the buffer-cylinder 30, the rod 1 passing with a 5 close fit through partition-wall 33 in the buffer-cylinder. A small passage 34 through the partition-wall 33 is controlled by a screw or stop-valve 35. This valve may be adjusted so as to open passage 34 to a greater or less 10 extent. As the piston-rod 1 is thrown in either direction the buffer-piston 31 from the driven end of the rod will enter the cylinder 30, and the air ahead of this buffer-piston will be compressed, escaping through the opening 15 34 with more or less rapidity, according to the position of stop-valve 35. The buffer or check does not begin to operate until the stroke is within one and one-half inches of completion, said buffer or check eliminating all jar 20 and shocks.

As soon as either lever 11 is operated to release the pressure on valve-stem 6 spring 13 will lift said stem, closing plug 8 into its seat and excluding further air entrance into cylinder 3. The air from said cylinder will then escape through opening 16, and the cylinder will offer little resistance to the return movement of piston 2 when driven from the other side of the loom.

From the foregoing it is believed the construction and operation of this device will be understood by experts in this art. The mechanism is simple and light, of few parts, which reduces wear and cost of maintenance, and can 30 be adjusted to almost any kind of loom now constructed. The thrower is carried on the lay of the loom and suitable operative connections can be made by an expert mechanic. By simply increasing the air-pressure the 35

shuttle speed is increased, thereby enabling 40 the revolution of the loom to be increased, increasing the output.

What we claim is—

1. In a pneumatic shuttle-thrower, the combination of a cylinder at each side of the loom, 45 a piston-rod extending across the loom and having shuttle-throwers connected thereto, and a pneumatic buffer connected to said piston-rod.

2. In pneumatic shuttle-throwers, a pneu- 50 matic cylinder at each side of the loom, pistons in said cylinders, a piston-rod extending across the loom and connecting said pistons, shuttle-throwers connected to said piston-rod, and buffers to check the movement 55 of the rod, all the specified elements combined substantially as described.

3. In a pneumatic shuttle-thrower, the combination of a pneumatic cylinder, piston, and means whereby the shuttle is operated 60 from said piston, and an adjustable pneumatic buffer whereby the piston movement may be arrested.

4. In a pneumatic shuttle-thrower, the combination of a pneumatic cylinder, piston, 65 and means connected to the piston whereby the shuttle is thrown, a valve controlling air-inlet to the cylinder, a spring for closing said valve, and a vent in the valve-stem by which pressure in the cylinder is relieved when the 70 valve is closed,

In testimony whereof we affix our signatures in presence of two witnesses.

EZEKIEL C. S. COBB.
SAM'L. T. MACMULLEN.
